UNITED STATES PATENT OFFICE.

CHARLES SHABLEY, OF LA SALLE, ILLINOIS.

APPARATUS FOR STORING AND PRESERVING BEER ON TAP.

SPECIFICATION forming part of Letters Patent No. 514,508, dated February 13, 1894.

Application filed February 21, 1893. Serial No. 463,197. (No model.)

To all whom it may concern:

Be it known that I, CHARLES SHABLEY, a citizen of the United States, residing at La Salle, in the county of La Salle and State of Illinois, have invented a new and useful Improvement in Apparatus for Storing and Preserving Beer when on Tap, of which the following is a specification.

My invention relates to apparatus for storing the beer when on tap and its object is to preserve the beer from the air and prevent the evaporation of its gases and to provide for ready and strong flow of the beer when being drawn from the vessel, and consists in the mechanical elements and combinations set forth in the claims hereof.

Reference will be had to the accompanying drawings, in which—

Figure 1 is a side view of the machine. Fig. 2 is a side sectional view. Fig. 3 is a side view transversely of Figs. 1 and 2. Fig. 4 is a plan of the lifting mechanism on the line 4, 4, of Fig. 1. Fig. 5 is a plan of the stop catch mechanism. Fig. 6 is a sectional view of the vent cock.

In the drawings, "A" designates a cylinder, being a chamber large enough to hold the contents of a beer keg designated by "B" in the drawings. This cylinder is supported on a bed frame "A'." Over the top of this cylinder there is a yoke "A²" resting on the edges of the cylinder, and fastened down at "a'" to posts "A³" fastened into the bed frame at "a." In the top of the yoke "A²" there is an aperture through which a piston rod "D" passes. At the bottom of this rod "D" there is a piston "C" which piston "C" is composed of a plate "C²" screwed to rod "D" at "C⁹" and above this on the rod "D" there is fastened at "C¹⁰" another plate "C'" and between these plates there is a ring "C³" carrying packing "C⁴." There is a little space at top and bottom of ring "C³" between the plates "C²" "C'" permitting an adjustment by the nut "C¹⁰" of the packing "C⁴." In the ring "C³" there is a circular recess "C⁵" extending around the ring and there are openings "C⁶" "C⁷" connecting this recess with the space between the plates "C'" "C²" and ring "C³" and in the top plate there are holes "C⁸" opening into the outer air. The objects of this construction are to insure

a perfect exclusion of the air from underneath the piston as water is poured on top of the plate "C'" and fills the interior space between the plates and the recess "C⁵," thereby aiding in the packing of the piston, as no excessive pressure is exerted by the piston. In the piston rod "D" there are notches "d" into which the pawl "e" operates. The pawl "e" is pivoted at "e'" into a lever "E" which is pivoted at "E'" in the yoke "A²." The pawl "e" has two engaging points "e⁶" "e⁷" to engage the notches "d" in lifting and in lowering the piston. The pawl "e" is fixed to the axis "e'" which articulates in the bearings of the lever "E" and is held in engagement of either point "e⁶" "e⁷" by a weighted lever "e²" which revolves on the axis "e'." In the axis "e'" there is a stop "e⁸" on one side only of the axis and the lever "e²" has two projections "e⁴" "e⁵" on its hub, which engage the stop "e⁸" to hold either end of the pawl "e" in engagement with the notches "d" of the rod "D." The position shown in Fig. 1, the projection "e⁴" rests against the stop "e⁸," but in the dotted position of the same figure, the projection "e⁵" rests against the stop "e⁸." On the other side of the rod "D" there are notches "d'" into which a locking bolt "F" engages, to hold the rod "D" in any desired fixed position. This bolt "F" is held in engagement by a spring "f³" and its outer end is beveled to permit it to slip by notches "d'" in one direction. To the outer end of this bolt "F" there is a handle "f'" which, when the bolt is drawn back sufficiently for the end to clear the notches "d'" of the rod "D," may be revolved past the end "f²" of the block "f'" and lock the bolt "F" out of engagement and the handle "f'" may be revolved to reverse the bevel of the end of the bolt "F" to permit it to slip notches in other directions of movement of rod "D."

On top of rod "D" there is a round projection "d²" on which there is placed when desired a weight "W" shown dotted in Figs. 1 and 2. Into the bottom of the cylinder "A" there are cocks "G'" "g'" "G³." "G'" connects to a beer fountain not shown. "G³" is a drain cock. "g'" connects a rubber pipe "G" which connects a cock "g" in the beer keg "B." In the top of the beer keg "B" there is a vent cock "G²" shown in section in

Fig. 6, which is provided with openings "g²" opening upward on the inside of the cask.

The desideratum of the whole apparatus is to keep the air from the beer, and as the air rushes into the vent "G²" it diffuses itself in the top of the cask out of the openings "g²," which if the vent were a straight opening would impinge on the surface of the beer, displacing the gases of the beer and exposing the beer to further action of the air, which I am trying to prevent.

The operation of the device is thus: The cask of beer "B" is connected up as shown with the rubber hose "G" and cocks "g" "G²" "G³" closed and "g'" open, and the piston "C" in position shown. The operator then, by the lever "E" lifts the piston, sucking all the air possible out of the rubber pipe "G" collapsing the same. Then he closes the cock "g'" and opens "G³" and then forces down the piston, thereby expelling all the air possible from the cylinder and pipes. Then he closes cock "G³" and opens "g" "g'" ("G'" being closed). He lifts the piston again by the lever "E" drawing the beer from the cask "B" into the cylinder and when the same is drawn he closes cock "g'" and puts on his weight "W" on the rod "D" and disengages the catches "e" and "F," and connects his beer fountain by the cock "G'" and the weight on the piston forces the beer out as he draws upon it by the fountain, which operation of the apparatus excludes the air entirely at all times, which is a desideratum, and keeps

his beer under sufficient pressure to flow at all times.

What I claim is—

1. An apparatus for storing beer on tap, consisting essentially of a cylinder "A," a piston "C," a piston rod "D," with notches "d," a lever "E," carrying a pawl "e," having two engaging points "e¹"—"e²," and a reversible weighted lever "e²," for holding either engaging point of the pawl "e," in engagement with the notches "d," as shown. 45

2. An apparatus for the purpose described. Having a cylinder "A," piston "C," piston rod "D," having notches "d" in its edges. Lever "E," carrying pawl "e," engaging said notches "d," and projection "d²" on rod D, 50 fitted to hold weights thereon, and weights "W," as shown.

3. An apparatus for the purpose described. Having the cylinder "A," piston "C," piston rod "D," supported at top by yoke "A²," and having a locking bolt "F," actuated by a spring "f³," and having the beveled end "f'" and projection "f'" arranged as shown, whereby the bolt may be made to lock the movement of the piston rod in either direction, as desired, substantially as shown. 60

In witness whereof I have hereunto subscribed my name in the presence of two witnesses.

CHARLES SHABLEY.
